UNITED STATES PATENT OFFICE.

LAWRENCE C. MOONEY, OF MONTGOMERY, ALABAMA.

CROSS-TIE FOR RAILWAYS.

1,096,315.

Specification of Letters Patent. Patented May 12, 1914.

Application filed March 13, 1913, Serial No. 754,118. Renewed October 11, 1913. Serial No. 794,718.

To all whom it may concern:

Be it known that I, LAWRENCE C. MOONEY, a citizen of the United States, residing at Montgomery, in the county of Montgomery and State of Alabama, have invented new and useful Improvements in Cross-Ties for Railways, of which the following is a specification.

This invention relates to an improved cross-tie for the permanent way of a railroad which shall be stronger, relatively cheaper and more durable than cross-ties now in common use.

The object of this invention is the production of a novel cross-tie, made of concrete or other suitable plastic material, containing wooden blocks or sections near each end to serve as resilient rail seats, and reinforced by longitudinal bars or rods of metal extending to each end of the tie through the wooden sections or pillow blocks. As a further reinforce for the tie a cradle of interlaced rods or reticulated metal is embedded in the concrete beneath each pillow block, the ends of which cradles incline upwardly into the body of the tie and there terminate in the form of loops or hooks, said cradles serving to strengthen that portion of the cross-tie below the blocks, and which is thinner than in any other portion, from the hammer-like blows of the wheels of passing trains.

The improved tie is of rectangular cross-section with parallel vertical sides and parallel top and bottom the latter having a shallow central recess for about one-third its length extending across the tie from side to side.

The wooden sections or pillow blocks extend entirely across the tie and are retained in place by the longitudinal reinforcing members, projections on the sides of the blocks embedded in the concrete, and concrete ribs covering a portion of the lower ends of the blocks which are chamfered at their corners for this purpose. Resting on each pillow block is a seat plate for the rail, the ends of which are turned down over the ends of said blocks and covering the upper part thereof, which in connection with the concrete extending over the chamfered lower portion of said block ends, leave very little of said block exposed to the elements.

To more fully disclose the novel features

of the invention, attention is directed to the accompanying drawings forming a part of this specification and in which—

Figure 1 is a top plan view of a cross-tie with a portion of two rails spiked thereto. Fig. 2 is a perspective view of two pillow blocks connected together by a tie rod. Fig. 3 is a side elevation of the cross-tie. Fig. 4 is a vertical longitudinal sectional view of the same. Fig. 5 is an enlarged cross-sectional view on the line 5—5 of Fig. 4. Fig. 6 is an enlarged end view of one of the pillow blocks. Fig. 7 is a horizontal sectional view of the cross-tie. Fig. 8 is a perspective view of the reinforcing cradle. Fig. 9 is a view similar to Fig. 6 showing a modified form of the cradle. Fig. 10 is a perspective view of the modified cradle.

In the drawings, in which like reference characters are used for the same parts in all the figures, A indicates the cross-tie as a whole made of plastic material, such as cement concrete strengthened by metal rods or bars and provided with wooden sections or pillow blocks to support the rails and receive the fastening spikes.

The improved cross-tie is of the usual length, height, and width but is preferably formed with a shallow recess, or depression 10, in its underside for about one-third its length to give a firm seat to the cross-tie beneath the rails and permit the material forming the road bed to collect between the rails which, owing to the hammering of the wheels of passing trains, it has a natural tendency to do, without interference from or binding the cross-ties. This recess or depression by permitting the material to collect or be filled in between the rails tends to prevent longitudinal creeping of the ties.

Embedded in the cross-tie near each end is a wooden section or pillow block 11 of less height than the cross-tie but extending entirely across the same, the ends and the upper surfaces of the pillow blocks being flush respectively with the vertical sides and top of the cross-tie. Similar frusto pyramidal projections 12 extend from opposite sides of the pillow blocks in the longitudinal center 105 of the cross-tie and are embedded in the concrete forming the same. A perforation extends through each block and said projections to receive a longitudinal tie bar 13 threaded at its ends for nuts 14 which when 110

screwed into place bear firmly against binding plates 15 seated against the outermost projections 12 and having flanged edges which overlie the upper and lower surfaces of the same. Reinforce bars or rods 16 extend from end to end of the cross-tie and may be arranged in any desired order, as for instance in two horizontal rows, one above and one below the tie rod 13. The ends of these reinforce bars or rods are preferably bent downward in the form of hooks to more firmly anchor the rods in the concrete.

Supported on each pillow block 11 is a seat plate 17 for a railroad rail said plate being as wide as the block and having downwardly flanged ends 18 which project over the ends of the pillow block and cover the upper portions of the same. The said plates 17 have the usual flanges 19 on their upper surfaces between which the rails rest and openings 20 through which the spikes are driven into the pillow blocks.

It is to be noted that owing to the insertion of the pillow blocks in the cross-ties the amount of concrete material below said blocks is small as compared with the rest of the cross-tie and unless some means were provided for strengthening this end portion it would prove an element of weakness. To overcome this seeming defect a reinforce element in the form of a cradle 21 is embedded in the concrete of the tie beneath each pillow block, the ends 22 of which element incline upwardly toward the center of the cross-tie and there terminate. These ends are preferably made of hooks or returned bends 23 to firmly anchor the cradle in position. Such a cradle gives a firm support to the cross-tie, transmitting the weight of passing trains and the hammer-like blows of their wheels from the thin section of concrete 24, beneath the blocks, to the body of the cross-tie. The ends of the cradle being bent, as shown, hook into the concrete and form what may be termed a swinging cradle in which the pillow block is suspended. These cradles are preferably made of bars or rods, interlaced or crossed, as clearly shown in Fig. 8, but if desired such cradles may be made of plates of reticulated metal as shown in Fig. 10. The lower corners of the pillow blocks 11 above the thin portion 24 of the cross-tie are cut away or chamfered, as at 25, and such cut away portions filled with concrete thus forming upstanding ribs or braces 26 which tend to strengthen the thin portion 24 and also serve to cover the lower parts of the ends of the pillow blocks. These ribs 26 covering the lower part of the pillow block ends, and the flanges 18 on the seat plate 17 covering the upper parts of the same ends, leave but little of said blocks exposed to the elements and other destructive agencies, thus tending to lengthen

the life of said blocks, which may be further protected by treating them with creosote or other suitable wood preservative.

It is to be noted that the pillow blocks 11 are symmetrical in their formation. At each end of the bottom of said block is a chamfered corner 25, and on each side is a frusto-pyramidal projection 12 similarly disposed with relation to the axis of the opening therein through which the tie-rod 13 passes. From this it will be evident that in assembling the parts to form the tie either side of the block with a projection may be placed outermost or toward the end of the tie, or a block may be placed at either the right or the left thereof, the blocks being symmetrical it is immaterial at which end of the tie they are placed; or which side faces the tie end.

In the manufacture of this improved cross-tie the tie rod 13 is run through the central opening in the pillow blocks, the bearing plates 15 placed over the ends of said tie-rod in position on the projections 12, and the nuts 14 screwed firmly against the plates holding said pillow blocks the proper distance apart. The reinforce rods or bars 16 are then threaded through suitable openings in the pillow blocks and their ends bent upon themselves as shown. This skeleton structure is now placed in a mold of suitable shape, within which have been positioned and suitably secured cradles 21, and concrete poured into said mold in the usual manner. After hardening, the cross-tie is removed from the mold and finished in well known manner.

What I claim is:

1. A cross-tie made of concrete having a rail supporting pillow block embedded therein near each end, reinforcing members embedded longitudinally of said tie and engaging said pillow blocks, and an independent reinforcing element embedded in said tie beneath each pillow block with its ends projecting beyond the sides of the pillow blocks into the body of the tie.

2. A cross-tie made of concrete having a rail supporting pillow block embedded therein near each end, reinforcing members embedded longitudinally of said tie and engaging said pillow blocks and an independent reinforce member embedded in said tie beneath each pillow block, the ends of said independent member extending beyond the sides of the pillow block and being inclined upwardly into the body of the tie.

3. A cross-tie made of concrete having a rail supporting pillow block embedded therein near each end of less height than said cross-tie and flush with the top thereof, reinforce bars or rods embedded in the concrete between said pillow blocks, and a reinforcing member beneath each pillow block also embedded in the concrete, its ends in-

clining upwardly into the body of the tie and terminating near the middle thereof.

4. A cross-tie made of concrete having a rail supporting pillow block embedded therein near each end of less height than said cross-tie and flush with the top and vertical sides thereof, reinforcing bars or rods embedded in the concrete between said pillow blocks and extending through them to the ends of the cross-tie, and a reinforcing cradle beneath each pillow block also embedded in the concrete, the ends of which incline upwardly and terminate near the middle of the tie.

15 5. A cross-tie made of concrete having a rail supporting pillow block embedded therein near each end of less height than said cross-tie, the opposite vertical faces of which block are symmetrical and parallel and may be assembled without regard to right and left position, a facial projection on each of the two opposite sides of each block embedded in the concrete, and chamfered lower corners on the ends of the blocks which are filled out with concrete to form strengthening flanges for the concrete below the pillow blocks and to overlie the lower part of the ends of said blocks and protect them from the elements.

25 30 6. A cross-tie made of concrete having a wooden rail supporting pillow block embedded therein near each end of equal width and less height than said cross-tie, and flush with the top thereof, similarly shaped projections on the sides of said blocks embedded in the concrete, a tie-rod having threaded ends which extend through the pillow blocks and through the projections thereon, a plate bearing against the outer 35 projection on each block, fastening means on the threaded ends of the rod pressing said plates against the projections, reinforced bars extending from end to end of the tie through the pillow blocks and a reinforcing cradle beneath each pillow block embedded in the concrete.

40 45 7. A cross-tie made of concrete having a rail supporting pillow block embedded therein near each end of equal width and less height than said cross-tie and flush with the top thereof, similar shaped projections on the sides of said blocks embedded in the

concrete, a tie-rod between and connecting said pillow blocks, said tie-rod extending through the projections thereon, chamfered lower corners on the ends of the blocks flush with the vertical sides of the tie and filled out with concrete to form strengthening flanges for the tie below the pillow block and to overlie the lower part of said block 55 ends and protect them from the elements, and a rail seat plate on each of said pillow blocks of equal width with said block and having flanged ends extended downward and covering the upper part of the ends of the blocks.

8. A cross-tie made of concrete having parallel sides and parallel top and bottom, a shallow longitudinal depression being formed in said bottom across the tie intermediate its ends, a rail supporting pillow block embedded in the tie between the shallow depression and each end of the tie and of less height than the tie, said blocks extending entirely across the tie and flush with the top thereof, metal reinforcing bars extending from end to end of the tie through the pillow blocks, and a reinforcing member beneath each pillow block wholly embedded in the concrete, the ends of which member incline upwardly into the body of the tie and terminate near the middle thereof.

9. A reinforcing member for a concrete railway cross-tie comprising an independent cradle like structure of metal arranged horizontally beneath the rail supporting area of the tie and having upturned angularly disposed ends terminating in hook shape projections.

10. A reinforcing member for a concrete tie comprising an independent cradle like structure made of interlaced or crossed bars of metal arranged horizontally beneath the rail supporting area of the tie, and the ends of the longitudinal bars being bent upwardly at an inclination and each terminating in a hook.

In testimony whereof I have hereunto set my hand in presence of two subscribing witnesses.
